UNITED STATES PATENT OFFICE

JOHN W. SMITH, OF CLEVELAND, OHIO

CASTING MACHINE

Application filed December 3, 1928. Serial No. 323,407.

This invention relates to metal founding, and more particularly to a new and novel centrifugal casting machine wherewith the casting of articles from molten metal may be promoted and facilitated and an improved product obtained. Briefly stated, the machine is particularly constructed to support a sectional mold in quick detachable connection with a rotatable disk. Means for delivering the molten metal into the mold also forms an essential working part of the machine, and the delivery means is movably supported and adjustable vertically in respect to the rotatable disk to accommodate molds of different height. The delivery means is also especially constructed so that it may be tilted and rotated to direct a stream of molten metal at a given angle against the vertical side walls of a rotating mold, or into molds in which the inner walls are located different distances from the axis of rotation. The machine also includes other desirable features as hereinafter shown and described and more concisely set forth in the claims, but in general my object is to provide a machine which will simplify and expedite casting operations and produce a dense and homogeneous casting free from internal cavities and defects.

In the accompanying drawings, Fig. 1 is a sectional view of the machine in a vertical plane, and Figs. 2 and 3 are top views and front elevations respectively. Figs. 4 and 5 are cross sectional views of the machine on horizontal lines 4-4 and 5-5, respectively, of Fig. 3. Fig. 6 is a horizontal section of the base portion of the machine, on line 6-6 of Fig. 3. Fig. 7 is an enlarged sectional view of the mold and pouring crucible, operatively related as in use, and showing the molten metal being delivered against the inner circular wall of the mold and flowing by gravity downwardly thereover and upon itself while the mold is under rotation.

The machine comprises a main frame which includes a bed plate 2, a flat table 3 mounted upon posts 4 bolted to the bed plate, and a channeled upright or standard 5 secured to corresponding sides of the bed plate and table by angle-iron connecting pieces 6. A screw-

threaded shaft 7 is journaled at its upper and lower ends in brackets 8 riveted to standard 5 within its channeled front, and a pair of bevel gears 9 and 10, respectively, together with a hand wheel 11, serve to rotate the screw shaft when the operator wishes to produce vertical travel of a nut 12 in the channel. A laterally-extending arm 14 is attached to the front of nut 12, and a rigid shaft 15 projects forwardly from one end of arm 14 over a rotatable disk A situated centrally above table 3. A sleeve or tube 16 having telescopic connection with horizontal shaft 15 is provided with a supporting ring or yoke 17 at its outer end wherein a delivery pot or hopper B may be rotatably seated in a tilting position above the open end of a mold C clamped upon the top of disk A. A thumb screw 18 or other suitable means fastens telescopic sleeve 16 to shaft 15, and when this thumb-screw is released the hopper may be shifted forwardly or rearwardly relatively to mold C and the vertical axis of disk A, or sleeve 16 which supports hopper B may be slipped free from shaft 15 and the hopper bodily removed therewith from the machine without disturbing the mold or any other part. A rounded or spherically-shaped enlargement 19 annularly of hopper B rests within a correspondingly-shaped seat in ring 17 to permit the hopper to be tilted within limits, thereby permitting the delivery spout 20 of the hopper to be raised or lowered and the angle of inclination thereof changed relatively to the open mouth of mold C. Set screws 21 in the sides of ring 17 may be used to lock and hold the hopper in any inclined position, and also against rotation after the hopper has been turned within the ring to place spout 20 in any desired tangential relation to the circular wall of the mold, say as indicated by the dotted lines a-a and b-b, in Fig. 4. The proper delivery of the stream of molten metal issuing from spout 20 against the curved inner wall of the mold is important in operating this machine, and the means outlined above permits varied adjustments of the hopper and its spout to be easily made preliminary to charging the mold. Furthermore, various settings may be

readily obtained with molds of different kinds, for example, molds of different diameter, and to promote the making of molded objects of different diameter, either solid or tubular, the present mold is provided with a number of circular linings 22, which together with the mold body are split longitudinally and divided into separable sections to facilitate assembly and disassembly. Thus 5 the main body of the mold is made in two semi-circular sections hinged together at one side so that it may be opened readily to remove the molded product, and the lining sections 22 are likewise made of semi-circular 10 sections which abut or come together on the parting line of the main mold walls, see Fig. 5. The base portion 23 of one of the main mold sections is flanged and circular to permit a set of clamping elements 24 to be drawn 15 down thereon by bolts 25 having heads adapted to slide back and forth in ribbed or undercut channels 26 radially at the top of disk A, thereby permitting molds of different diameters to be detachably connected with the 20 disk. The bottom of the mold is also provided with a central aperture 27 to fit the reduced extension or tip 28 of the driving shaft 29 for the disk. In that way the mold may be accurately centered in respect to 25 the axis of revolution and an eccentric position easily avoided when the mold is placed upon the disk. In casting a tubular product, for example, a cylindrical bearing of bronze or other alloyed metals, a round core member 30 having a tapered projection 31 of reduced diameter at its lower end is introduced into the mold. Tapered projection 31 is seated in a tapering opening 32 in the top face of the closed bottom of the mold, and to completely 35 center the core member its upper end is then engaged by a pointed centering and holding screw 33 which is carried by a bar 34 having a pivotal or hinge connection with nut 12, see Fig. 4. Accordingly when the mold is 40 placed into position, or removed from disk A, bar 34 and its screw may be lifted and tilted back against the standard out of the 45 way.

Disk A is revolved or rotated at a predetermined speed by driving shaft 29, which is supported in an upright position by a suitable bearing 35 in table 3 and by a ball bearing 36 at its lower end. A pulley 37 is keyed 50 to shaft 29, which pulley encloses the ball bearing structure 36 fastened to bed plate 2, and power is applied to pulley 37 by a belt 38 which passes around a pair of idler pulleys 39-39 at opposite sides of standard 5, see Fig. 6. Belt shifting devices may be used to 55 throw the power on and off from a line shaft as commonly, and this device is not shown herein, as any known means of applying power to shaft 29 may be utilized. However, it is desirable in a centrifugal casting ma- 60 chine of this type to have a ready means of

controlling the speed of rotation of the mold, and to stop it independently of the power at the source in emergencies. For that purpose I mount a brake shoe 40 upon an oscillatory shaft 41 opposite drive pulley 37, see Fig. 1, 70 and provide a foot treadle 42 (normally held in a raised position by a spring 43) to rock shaft 41 and apply braking friction to the pulley. 75

What I claim, is:

1. In a centrifugal casting machine, a rotatable support for a mold, a receptacle for delivering molten metal to the mold, and means for supporting said receptacle adjustably in different delivery positions opposite the mouth of the mold. 80

2. In a centrifugal casting machine, a mold rotatable about a vertical axis and open at its upper end, a receptacle for the molten metal having a discharge outlet opposite the open end of said mold, and a shiftable support for said receptacle to permit the discharge outlet to be placed closely to the inner wall of said mold. 85

3. In a centrifugal casting machine, an open mold having removable interchangeable linings, means for rotating said mold about a vertical axis, and a receptacle for delivering molten metal into said mold, said receptacle being adjustably supported to permit different delivery relations to be established upon interchange or removal of said linings. 90

4. In a centrifugal casting machine, rotatable means for supporting open molds interchangeably in an upright position, a receptacle for delivering molten metal into a mold mounted upon said means, and a device for supporting said receptacle adjustably in respect to the opening in any particular mold mounted upon said rotatable means to permit a stream of molten metal to be discharged against the inner wall of that mold. 100

5. In a centrifugal casting machine, a rotatable support for interchangeable molds, a receptacle for delivering molten metal into any given mold mounted upon said support, and means for raising and lowering said receptacle relatively to the upper end of the mold. 110

6. In a centrifugal casting machine, means for supporting molds interchangeably in corresponding upright rotatable positions, a receptacle for delivering molten metal into the upper end of any given mold so supported, means for adjusting the delivery position of said receptacle laterally in respect to the wall of any given mold, and means for adjusting the vertical placement of the receptacle relatively to the upper end of any given mold. 115

7. In a centrifugal casting machine, a mold supporting member rotatable about a vertical axis, means for centering and securing a mold upon said member, a receptacle for delivering molten metal into the upper end of the 120

centered mold, and means for positioning tal extensible supporting device for said receptacle in offset relation to said vertical axis.

8. In a centrifugal casting machine, a rotatable member, means for securing an open mold removably in an upright position upon said member, a standard at one side of said rotatable member, and a receptacle detachably connected to said standard for delivering metal into the upper end of the mold.

10. 9. In a centrifugal casting machine, a channeled member mounted to rotate about a vertical axis, a sectional mold having a base flange adapted to be seated centrally upon said member, and shiftable means within said channels for clamping said flange rigidly to said member.

10. In a centrifugal casting machine, a mold supporting member rotatable about a vertical axis, a mold removably seated upon said member axially co-incident with said axis, a central core extending through said mold, and a shiftable centering and holding device for the upper end of said core.

11. In a centrifugal casting machine, a rotatable mold supporting member, an open mold seated upright upon said member, a core for said mold exposed at the open end of said mold, a centering holder engageable with the exposed part of said core, a receptacle for delivering molten metal into the open end of said mold, and means for effecting vertical adjustments of said receptacle and core holder to accommodate molds of different height.

12. In a centrifugal casting machine, a rotatable mold having a separate core, a receptacle for delivering molten metal into said mold, a holder for said core, and a common means for elevating and supporting said delivery receptacle and core holder.

13. In a centrifugal casting machine, a rotatable mold supporting member, a standard at one side of said member, an elevating device supported by said standard, a receptacle for delivering molten metal into a mold seated upon said rotatable member, said receptacle being detachably connected with said elevating device, and hinged means for holding a core member centrally within the mold.

14. In a centrifugal casting machine, a frame and a vertical shaft rotatably mounted therein, a mold supporting member and a brake wheel affixed to said shaft, a delivery receptacle mounted upon said frame above said mold supporting member, and a manually operable braking device associated with said brake wheel to control the speed of revolution of said shaft and mold supporting member.

15. In a centrifugal casting machine, means for rotating a mold about a vertical axis, a receptacle for delivering molten metal into the upper end of said mold, a horizon-

tal extensible supporting device for said receptacle, and screw means for elevating and lowering said supporting device.

16. In a centrifugal casting machine, a rotatable support for a mold, a receptacle for delivering molten metal into the mold, a horizontally-adjustable support for said receptacle, means for elevating and lowering the said support for said receptacle, and said receptacle being capable of rotatable adjustment relatively to the mold.

In testimony whereof I affix my signature.
JOHN W. SMITH.
